(57) CLAIM

I claim the ornamental design for a portable pushups exercise device, as shown and described.

DESCRIPTION

FIG. 1 is a perspective view of a portable pushups exercise device showing my new design;

FIG. 2 is a front elevational view thereof; the rear elevational view being identical thereto;

FIG. 3 is a side elevational view thereof, the opposite side elevational view being identical thereto;

FIG. 4 is a top plan view thereof;

FIG. 5 is a bottom plan view thereof; and,

FIG. 6 is a perspective view showing the portable pushups exercise device in use; the broken lines depict environmental structure and form no part of the claimed design.
